(57) **CLAIM**

The ornamental design for a scarecrow owl head as shown and described.

DESCRIPTION

FIG. 1 is a front perspective view of a scarecrow owl head of my new design.

FIG. 2 is a front view thereof.

FIG. 3 is a rear view thereof.

FIG. 4 is a right-side view thereof.

FIG. 5 is a left-side view thereof.

FIG. 6 is a top view thereof.

FIG. 7 is a bottom view thereof; and,

FIG. 8 is a perspective view of the scarecrow owl head shown in a state of use on a scarecrow body.

The broken lines in the drawings illustrate environment and form no part of the claimed design.

1 Claim, 8 Drawing Sheets
